UNITED STATES PATENT OFFICE.

C. E. STOCKDER, OF WEST MERIDEN, CONNECTICUT.

IMPROVEMENT IN BRIDLE-BITS.

Specification forming part of Letters Patent No. 39,843, dated September 8, 1863.

To all whom it may concern:

Be it known that I, C. E. STOCKDER, of West Meriden, in the county of New Haven and State of Connecticut, have invented a new and useful Improvement in Bridle-Bits; and I do hereby declare that the following is a full, clear, and exact description of the same, reference being had to the accompanying drawings, forming a part of this specification, in which—

Figure 1 represents a plan or top view of my bridle-bit, when the same is stretched out and laid down flat. Fig. 2 is a longitudinal vertical section of one of the rings, showing the application of the strap.

Similar letters of reference in both views indicate corresponding parts.

This invention consists in the arrangement of an eye and tongue in the bit-ring in such a manner that the end of the rein can be fastened directly in the bit-ring itself, thus avoiding the necessity of doubling up the strap and without the application of an extra buckle and martingale-stop, whereby the manufacture of the rein is rendered much cheaper than that of ordinary reins; and, furthermore, by the use of my bit-rings the reins are made of a uniform thickness throughout, and therefore not liable to crook and break.

To enable those skilled in the art to make and use my invention, I will proceed to describe it.

A A represent the bit-rings, which are made of malleable iron or any other suitable material, and which are connected by the bit B in the ordinary manner. Each of the rings

A is provided with a tongue, a, and eye b, to receive one of the ends of the rein C. These ends are provided with a series of holes, c, so that they can be shortened or lengthened at pleasure, and that they can be secured to the bit-strings without the aid of an additional buckle. The rein can thus be made of one uniform thickness throughout, and by dispensing with the extra buckle the martingale-stop can also be dispensed with, there being no place in my rein in which the martingale-ring might possibly catch.

In an ordinary rein at that place where the martingale-stop is applied three thicknesses of leather are secured—one on the top of the other—and the strap is liable to break on account of this inequality in its thickness, that portion of the strap close behind the thickest part acting like a joint which works continually backward and forward.

By my improvement I am enabled to make the billet and rein all out of one piece, and if the rein is to be round only the ends of the strap are left flat to enter the eyes in the bit-rings. The cost of manufacturing a rein is thereby considerable reduced, and an article of superior durability is produced.

What I claim as new, and desire to secure by Letters Patent, is—

As a new article of manufacture, a bit-ring, A, provided with a tongue, a, and eye b, as and for the purpose specified.

C. E. STOCKDER.
